UNITED STATES PATENT OFFICE

HENRY J. SCHLUTER, OF CHICAGO, ILLINOIS, ASSIGNOR TO J. C. DEAGAN, INC., OF CHICAGO, ILLINOIS, A CORPORATION OF ILLINOIS

LEVER MECHANISM

Application filed December 10, 1928. Serial No. 324,928.

My invention relates to lever mechanism which is operated by pedals and resides in the provision of means whereby the pedals may be shifted without the necessity of shifting the elements whose movement is to be effected by the pedals with the result that the pedals may be shifted to suit the convenience and purpose of the operators thereof.

My invention is of particular utility when employed for controlling the application and release of sound dampeners which are normally applied to sound producing bars of musical instruments of the xylophone type although the invention is not to be limited to any particular use thereof.

The invention will be more fully explained by reference to the accompanying drawings in which Fig. 1 is a plan view of a xylophone type of instrument with parts broken away, the pedal mechanism of my invention being also illustrated, one position of the pedal being indicated by full lines and another position by dot and dash lines; Fig. 2 is a sectional elevation on line 2—2 of Fig. 1; Fig. 3 is a sectional elevation on line 3—3 of Fig. 1; Fig. 4 is a sectional view on line 4—4 of Fig. 5; Fig. 5 is a sectional view on line 5—5 of Fig. 4; and Fig. 6 is a perspective view illustrating some of the parts of the preferred construction in separated relation.

The musical instrument to which the pedal mechanism is applied will generally be described in connection with Figs. 1, 2 and 3. The musical instrument shown is of the xylophone type, the sound bars 1 being preferably of metal rather than of wood. These bars are usually arranged in two banks as illustrated in Fig. 1 and are of such proportions as to produce tones of the chromatic scale when they are set into vibration. The bars are usually threaded upon strings 2 which are anchored at their ends to posts 3. These posts are carried upon suitable framework 4 and are preferably provided with open slots into which the ends of the string may be downwardly passed.

The string ends are knotted as indicated at 5 to hold them in assembly with the posts 3. Other frames 6 are disposed below the bars and carry the upright resonating tubes 7 whose axes are aligned with the geometrical

centers of the bars, respectively. Each horizontal row of vibrant horizontal bars is provided with a unitary sound dampener which normally engages all the bars in such row and whose removal from the bars is required in order that the bars may be set into vibration. This unitary sound dampener is inclusive of a suitable horizontal mounting bar 8 which may be of wood or metal and upon whose top side a strip of felt 9 is disposed. A rod 10 is secured to and depends from the middle of the bar 8. A coiled spring 11 surrounds said rod. The upper end of this spring is seated in a cup 12 which presses against the bottom of the bar 8. The lower end of this spring is seated in a cup 13 which is carried by a plate 14. The plate 14 is seated at its ends upon two brackets 15 that are carried by the framework. This spring normally serves to press the sound dampener 9 against the bottoms of the sound producing bars 1. The sound dampener is maintained parallel with the rows of bars by means of two arms 16 which are connected with end portions of the bar 8 and which, themselves, are pivoted upon the framework 4. The pedal 17 is provided upon a pedal lever 18. This lever is pivoted upon an anchorage 19 which is secured to the strut 20 of the sub-framework 21 on which the frames 4 and 6 are carried. The pedal lever 18 is connected to the sound dampening bar 8 by means of linkage that is inclusive of the rod 10. This linkage is also inclusive of another rod 22 which is adjustably connected with the lower end of the rod 10. Rod 22 contains a turn buckle 23 by which its effective length may be varied to adjust the normal height of the pedal 17 from the floor. The sound dampening pressure of the spring 11 may be light and should be insufficient to raise the ends of the bars engaged thereby to any material extent. The spring, being light, the foot pressure upon the pedal 17 may consequently be light to withdraw the sound dampener from the sound producing bars.

The pedal is depressed to withdraw the sound dampener as long as it is desired to have successively produced tones intermingle, but when it is desired to stop the intermingling of successively produced tones the pedal is 100

released to permit the spring 11 to re-apply the sound dampener. The downward movement of the pedal is desirably limited by the floor, the range of movement of the pedal being regulated by the turn buckle 23 as is understood. The pedal desirably moves through a range of about $\frac{3}{8}$ of an inch.

The anchorage block 19 is supported from a hanger 24 which is carried by the framework 21. This hanger is horizontally deflected as indicated at 24'. This deflected portion 24' of the hanger is formed with a hole therethrough through which an upright screw 25 is passed. This screw is threaded into a block 26 having a semi-circular recess in its bottom side which receives the upper portion of the strut 20. The nut 25' upon the screw 25 is screwed down onto the deflected part 24' whereby the block 26 is anchored to the hanger. Another block 27 formed similarly to block 26 but symmetrically related thereto receives the lower side of said strut. Screws 28 secure the blocks 26 and 27 together and into clamping relation with the strut. The anchorage block 19 is assembled with the block 27 by means of an upright bolt 29 which is screwed into the block 27 but along which the anchorage block 19 is free to move. A coiled spring 30 is seated upon the head of the bolt 29 and presses upwardly against the anchorage block 19 to hold this block into engagement with the block 27. Teeth are provided upon the adjacent faces of the blocks 27 and 19, these teeth being radially disposed. The teeth upon these blocks intermesh so that block 19 is normally prevented from turning with respect to block 27. Two teeth upon one of these blocks, say the block 19, are sufficient to hold the blocks from relative turning movement. The block 19 carries two ears 31 between which the adjacent end of the pedal lever 18 is received and upon which this pedal lever is pivoted. When it is desired to change the position of the pedal the anchorage block 19 is depressed against the force of the spring 30 whereafter the pedal is horizontally swung to the desired position whereupon the anchorage block 19 is released to permit the spring 30 to press it upwardly and bring the teeth thereon into mesh with the contiguous teeth on the bottom of block 27. The link 22 has the connection of its lower end with the intermediate portion of the lever 18 flexible so that as the pedal is horizontally swung or shifted sidewise to change its position the lower end of said link may be shifted with the lever 18 without materially disturbing the inter-connection of the upper end of said link with the rod 10 or other part that is to be operated by the pedal.

Changes may be made without departing from my invention.

Having thus described my invention I claim:

65 1. The combination with a pedal and a le-

ver carrying it; of an anchorage upon which said lever is mounted, said anchorage being shiftable in position to permit sidewise adjustment of the pedal, wherein the anchorage is in the form of a block that is mounted to turn and wherein there is another block for positioning the anchorage block, said blocks having interengaging teeth for positioning the anchorage block.

2. The combination with a pedal and a lever carrying it; of an anchorage upon which said lever is mounted, said anchorage being shiftable in position to permit sidewise adjustment of the pedal; and a link connected at one end with said lever and connectible at its other end with the part that is to be pedal operated, wherein the anchorage is in the form of a block that is mounted to turn and wherein there is another block for positioning the anchorage block, said blocks having interengaging teeth for positioning the anchorage block.

3. The combination with a pedal and a lever carrying it; of an anchorage upon which said lever is mounted, said anchorage being shiftable in position to permit sidewise adjustment of the pedal; and a link connected at one end with said lever and connectible at its other end with the part that is to be pedal operated, the connection of one end of the link with the lever being flexible to permit this end of the link to accompany the lever in sidewise movement without materially disturbing the position of the other end of the link, wherein the anchorage is in the form of a block that is mounted to turn and wherein there is another block for positioning the anchorage block, said blocks having interengaging teeth for positioning the anchorage block.

4. The combination with a pedal and a lever carrying it; of an anchorage upon which said lever is mounted, said anchorage being shiftable in position to permit sidewise adjustment of the pedal, wherein the anchorage is in the form of a block that is mounted to turn and wherein there is another block for positioning the anchorage block, said blocks having interengaging teeth for positioning the anchorage block, and wherein a spring is employed normally to maintain the teeth upon the two blocks in mesh.

5. The combination with a pedal and a lever carrying it; of an anchorage upon which said lever is mounted, said anchorage being shiftable in position to permit sidewise adjustment of the pedal; and a link connected at one end with said lever and connectible at its other end with the part that is to be pedal operated, wherein the anchorage is in the form of a block that is mounted to turn and wherein there is another block for positioning the anchorage block, said blocks having interengaging teeth for positioning the anchorage block and wherein a spring is employed nor-

mally to maintain the teeth upon the two blocks in mesh.

6. The combination with a pedal and a lever carrying it; of an anchorage upon which said lever is mounted, said anchorage being shiftable in position to permit sidewise adjustment of the pedal; and a link connected at one end with said lever and connectible at its other end with the part that is to be pedal operated, the connection of one end of the link with the lever being flexible to permit this end of the link to accompany the lever in sidewise movement without materially disturbing the position of the other end of the link, wherein the anchorage is in the form of a block that is mounted to turn and wherein there is another block for positioning the anchorage block, said blocks having interengaging teeth for positioning the anchorage block, and wherein a spring is employed normally to maintain the teeth upon the two blocks in mesh.

In witness whereof, I hereunto subscribe my name.

HENRY J. SCHLUTER.
